UNITED STATES PATENT OFFICE.

PIOTR S. RACHWAL, OF DEPEW, NEW YORK.

RAILROAD-TIE.

1,373,831.

Specification of Letters Patent.

Patented Apr. 5, 1921.

Application filed March 21, 1919. Serial No. 284,159.

To all whom it may concern:

Be it known that I, PIOTR S. RACHWAL, a citizen of Poland, residing at Depew, county of Erie, State of New York, have invented 5 certain new and useful Improvements in Railroad-Ties, of which the following is a specification.

This invention relates to improvements in railway track equipment, and particularly 10 to the ties and means for securing rails thereon.

The principal object of the invention is to provide a hollow metallic tie, adapted to have rails secured upon its upper surface.

15 A further object is to provide means whereby the holding bolts are prevented from turning, the rails being clamped by clip elements engaged by the bolts in a secure manner.

20 These and other like objects are attained by the novel construction and combination of parts hereinafter described, and shown in the accompanying drawings, forming a material part of this disclosure and in 25 which—

Figure 1 is a top plan view showing a railroad tie made in accordance with the invention.

Fig. 2 is a longitudinal sectional view 30 taken on line 2—2 of Fig. 1.

Fig. 3 is an enlarged fragmentary top plan view parts being broken away in order to show the construction of the tie and rail secured thereto.

35 Fig. 4 is a vertical transverse section taken on line 4—4, Fig. 3.

In the drawings, the running rails are shown to be of the ordinary type comprising 40 heads 10, stems 11, and flanged base 12, of the ordinary rolled type.

In order to support the rails and hold them in proper spaced relation, one from the other, a metallic tie is used, the same having a relatively level upper surface 14, merged 45 into beveled side elements 15, terminating in longitudinally disposed vertical sides 16, the same adjoining similarly constructed ends 17, joined by the beveled connecting elements 18, all of the several parts being so 50 formed as to be readily made by ordinary processes of metal foundry practice.

Formed through the center face portion 14, are pairs of rectangular openings 20 and 20', the same being disposed at regularly

spaced intervals and staggered so as to avoid 55 alinement.

Extending outwardly from the openings 20 and 20', are rectangular recesses 21 and 21', it being understood that the main openings are adapted to receive the bolt heads 24, 60 while the stems 25 of the bolts may readily pass through the narrow recesses 21 and 21', the heads 24 being held from turning, when the bolt stems are within the recesses 21 and 21', by pairs of integrally formed lugs 23' 65 and 23'', positioned, one upon each side of the slots 21 and 21', at such a distance therefrom as to permit the head 24 to enter therebetween, thus preventing the same from being turned.

The bolts extend upward through openings in removable metallic plates 27, upon which the base flanges 12 of the running rails rest, and also pass through clips 28, formed with extensions 29, having a beveled 75 lower surface adapted to contact with the upper surface of the base flanges of the running rail, these clips being held in position by nuts 30 fitted to the upper ends of bolts 25.

In operation, the heads of the bolts are passed through the openings 20 and 20', the bolts extending through the ties, and entered in the slots 21 and 21', where the heads become engaged between the lugs 23' and 23'', preventing them from being turned. The plates 27 are then placed in position, over the bolts confining them from moving, the rail laid thereon, the clamping clips 28 29 placed over the flange of the rails and the 80 nuts applied holding the structure firmly clasped together, thus preventing either of the rails from moving.

From the foregoing it will be seen that an easily constructed metallic tie has been disclosed upon which a pair of running rails may be firmly clamped and rigidly secured in an easy and secure manner.

Having thus described my invention what I claim as new, and desire to secure by Letters Patent is—

1. In a railroad tie, the combination with a hollow elongated metallic casting having a substantially level top, rectangular openings arranged in staggered relation in pairs 100 in the top of said casting, relatively narrow recesses extending outward from said openings, said openings being adapted to receive 105

- heads of bolts, and said recesses the stems thereof, lugs formed upon the opposite sides of each of said recesses, adapted to engage with the heads of said bolts, a metallic cover 5 plate overlying said openings, said plate having openings through which the stems of said bolts extend and are prevented from moving inwardly, metallic clips engageable with said bolts on the upper side of said 10 plate, said clips having a portion adapted to engage with the upper beveled surface of the running rails, and nuts for securing said clips and plates on the surface of said tie, said nuts engaging with said bolts.
- 15 2. A railway tie comprising a hollow body having a top provided with an enlarged inner opening, a reduced recess extending outwardly from said opening, and lugs ar-

ranged underneath said top and on opposite sides of said recess, a clip adapted to engage 20 a rail on said tie, and a bolt having its stem passing through said clip and recess and having its head movable through said opening and normally arranged between said lugs so as to be held against turning thereby, and 25 the nut of the bolt bearing against the upper side of said clip.

In testimony whereof, I have signed my name to this specification in the presence of two subscribing witnesses, this 31st day of 30 January 1919.

PIOTR S. RACHWAL.

Witnesses:

MIKE PAWLAK,
STANISLAW BONAROUSKI.
